UNITED STATES PATENT OFFICE

LLOYD J. WHITE AND GEORGE L. YOUNGBLOOD, OF SAN ANTONIO, TEXAS, ASSIGNEES
TO SOUTHERN PRISON COMPANY, OF SAN ANTONIO, TEXAS, A CORPORATION OF
TEXAS.

CELL DOOR LOCKING AND OPERATING MECHANISM

Application filed May 9, 1930. Serial No. 451,142.

This invention relates to jails having master control systems for a series of cell doors and, among other objects, aims to provide a novel operating system whereby a keeper can unlock, open and lock open, or close and re-lock any number of selected doors by imparting continuous movement to a single master operating member without having to perform any intermediate operations. The main idea is to simplify and improve the operation of a modern and dependable system so as to enable a keeper quickly and expeditiously to release or lock up prisoners without making any mistakes.

Other aims and advantages of the invention will appear in the specification, when considered in connection with the accompanying drawings, wherein:

Fig. 1 (Sheets 1 and 2) is a fragmentary side elevation, partly in section, showing an illustrative example of the invention applied to the master control system of a plurality of cell doors;

Fig. 2 is a fragmentary top plan of the right hand end of Fig. 1, parts being omitted and other parts being shown in section;

Fig. 3 is a fragmentary top plan of the mechanism in Fig. 1 for imparting movements to a master lock operating bar and a door propelling bar;

Fig. 4 is a section on the line 4—4 of Fig. 1;

Fig. 5 is a fragmentary side elevation showing the positions of the links and levers when the cell doors are closed and locked;

Fig. 6 is a similar view but showing their positions when the selected doors are unlocked and closed;

Fig. 7 is a similar view showing their positions when the selected doors are partly opened; and

Fig. 8 is a similar view showing their positions after the doors are fully opened and locked open.

The illustrative example of the mechanism is here applied to a row of jail cells having sliding doors 10, vertically movable latch bars 11, a master lock operating member or bar 12, and a master door propelling member or bar 13. In this instance, the connections between the master bars and the in-

dividual locks and doors are controlled by selector devices 14 over each door connected to be selectively set or operated by selector rods 15. The whole system is so constructed and arranged as to be operated by mechanism, 55 including a lever or hand wheel 16 and a series of selector actuators or levers 17 projecting through a panel 18 at one end of the row of cells and conveniently housed in an inset control box 19.

The mechanism thus far described generally constitutes the subjects matter of Patents Nos. 1,785,471 dated December 16, 1930, 1,785,469 dated December 16, 1930. The former patent relates to the illustrated selector mechanism; while the latter patent relates to the inset control box. Hence, these details require no detailed description. Likewise, a number of other details which will not be specifically described herein are covered in 70 several patents and applications of D. F. Youngblood.

As viewed in Fig. 1, the doors slide to the left to open. They are shown as being closed and locked. When one or more of the doors are selected to be unlocked, (see the position of the selector 14 at the left end of Fig. 1) the master lock operating bar 12 is first moved to the left only a short distance; then, the master door propelling bar 13 is moved to the left carrying with it all selected and unlocked doors. Obviously, the movements are reversed to close and lock the doors. Also, all open doors are adapted to be locked open and unlocked automatically 85 incident to the foregoing operations.

Heretofore, the actuations of the master bars 12 and 13 have been effected either by means of separate levers (see Youngblood Patents Nos. Re. 17,403 and 1,269,244) or by 90 separate actuating movements of a single hand wheel or lever having associated transmission gearing. As shown in the patent of D. F. Youngblood, No. 1,785,470 dated December 16, 1930. While such actuators are 95 entirely practicable, a certain amount of skill is required to manipulate them quickly. Failure to follow directions may result in disastrous delays, especially when a jailer or keeper is handling desperate criminals. The 100

main idea of this invention is to eliminate some mechanism which requires manual actuation and mental contortions and, at the same time, to provide an improved and simple attachment which will automatically impart the necessary movements to both master bars or members incident to continuous movement of a single actuator lever or handle.

In Fig. 1, the preferred form of motion transferring mechanism is shown as being located in the usual housing above the cell gratings and between the first and second cell doors. For convenience, it is mounted on a supporting bracket 20 in form of a structural angle having one flange secured to the bottom wall 21 of the housing. A T-shaped rocker member having a short arm 22 connected at its end to the master bar 12 is shown as being pivoted to rock on a horizontal shaft 23 through the bracket 20 and also a small angle bracket 24 (Fig. 4). The arrangement is such that, when the arm 22 rocks or swings to the left, it will move the master locking bar sufficiently far to unlock all selected doors. The other arm of the T-shaped rocker is shown as being in the form of a channel member 25 (Figs. 3 and 4) to which the arm 22 is suitably secured, the open side of the channel facing the bracket 20 and the master door propelling bar being on the opposite side of the bracket.

To provide means for rocking the rocker member, a floating bell crank 26 is shown as being pivotally connected at its elbow to the master propelling bar 13 by means of a shaft 27 through said bar projecting through a longitudinal slot 28 in the bracket 20 and only part way into the channel of the arm 25. The shaft preferably has a flanged roller 29 to work in the slot and channel. The upper flange of the channel member 25 is cut away at 30 to permit the arm to rock about its own pivot or axis to the positions indicated in Figs. 1 and 5 when all doors are closed and locked. The other arm of the bell crank 26 has a fixed pin 31 normally projecting through an arcuate bayonet or locking slot 32 at the right hand end of the longitudinal slot 28 in the bracket and also into the bottom of the channel in the arm 25. This pin is also shown as having a flanged sleeve roller 33 working in the slot and in the channel. The arrangement is such that when the bell crank is swung to the left, as viewed in Figs. 1 and 5 to 8 inclusive, the pin 31 will swing out of the arcuate slot 32 in the bracket 20 until it strikes the top edge of the longitudinal slot 28, carrying with it the T-shaped rocker arm and moving the master bar 12 to the left (see the position of the parts in Fig. 6).

In Fig. 6, the channel arm 25 has been moved to a horizontal position so that the pivot pin 27 lies in the channel and can slide to the left. The next movement imparted to

the bell crank and the master door propelling bar is longitudinal and to the left, both pins 27 and 31 sliding in the channel 25 while the T-shaped rocker remains stationary. This longitudinal movement is imparted to the master propelling bar while the locking bar remains temporarily idle, all selected and unlocked doors being opened when the roller or pin 27 reaches the left hand end of the longitudinal slot, which is slightly longer than the channel arm 25 of the rocker. When this pin 27 strikes the end of the slot and is free of the channel arm, pivotal movement is again imparted to the bell crank swinging it farther to the left (Fig. 8) and moving the pin 31 into an arcuate slot 34 above the slot 28. The pin 31 remains in the channel of arm 25 and swings the arm to the position shown in Fig. 8, moving the locking bar 12 again to its locking position. Hence, the selected doors are then opened and locked open. The unlocking, door closing and relocking movements of the parts are effected by reversing the movements just described.

The bell crank 26 in this example is connected to be operated by the hand wheel 16, a bent link 35 being pivoted to the bell crank arm and arranged to reciprocate in the housing and operable in either direction by a single continuous movement of the hand wheel. Herein, a horizontal rack 36 is pivoted at one end to the link 35 and is guided to slide in a frame 37, meshing with a driving pinion 38 and an idler guiding pinion 39. A pair of guiding rollers 40 are shown as contacting with the upper edge of the rack to hold it engaged with the pinions. A longitudinal shaft 41 is suitably connected by bevel gears 42 to drive the pinion 38 and a shaft 43 of the hand wheel is geared to drive the shaft 41 conveniently by means of a sprocket chain 44. The length of the rack is greater than the width of a cell door opening and the arrangement is such that it is guided by the spaced pinions 38, 39 and the co-operating rollers 40 when it is moved to the left to open the doors. It will now be seen that a jailer or keeper needs only to manipulate the desired selector levers 17 before he starts and the whole cycle of operations may be completed by turning the hand wheel first in one direction and then in the other direction.

The action of the movement imparting mechanism to unlock, open and lock open all selected doors has been described in connection with Figs. 5 to 8 inclusive. The closing and relocking movements are effected by a continuous reverse movement of the hand wheel, moving the link 35, bell crank 26 and the associated parts to the right. The left end of the channel arm 25 is shown as being flared so as to guide pivot pin sleeve 29 into the channel. Also, a guide lip 45 is bent or struck up at the inner end of the

- notch or cut-away portion 30 in the upper flange of the channel to guide the pin 27 into the channel when the door opening movement is started.
- 5 Since the bell crank 26 swings the pin 31 into the bayonet or arcuate slots 32 and 34, the selected doors which are connected to the master propelling bar cannot be moved by a prisoner when they are either open or closed. The doors are also locked open or closed by the regular latches 11 so that they will remain locked when the selector mechanism is actuated by the selector levers 17 to release them from the operating mechanism.
- 10 Thus, the whole cycle of operations may be completed without any risk of having the doors tampered with by the prisoners. Moreover, the keeper is relieved of the necessity to follow any complex directions.
- 15 Obviously, the present invention is not restricted to the particular embodiment thereof herein shown and described. Moreover, it is not indispensable that all the features of the invention be used conjointly, 20 since they may be employed advantageously in various combinations and subcombinations.

What we claim is:—

1. A master locking and operating system 30 for a series of cell doors comprising a pair of master bars adapted to be selectively connected to said doors; and a common operating mechanism connected to both of said bars and arranged to be moved continuously in 35 one direction to impart lock actuating movement to one of said bars and door propelling movement to the other of said bars; said mechanism including means to hold either bar inactive while the other bar is being actuated.
- 40 2. In a master lock operating and door propelling system for a series of cell doors wherein independent master operating members are arranged to be connected to selected locks and doors, a single operating device connected to both members and having means initially to impart lock actuating movement to the master lock operating member and subsequently to impart door propelling movement to the master door propelling member.
- 45 3. In a lock operating and door propelling system for cell doors wherein independent operating members are arranged to be connected to selected locks and doors, a single hand wheel arranged at an operating station; and a system of links and levers operatively connected to the hand wheel and the members and arranged to impart lock actuating movement to the master lock operating member and then to impart door propelling movement 50 to the master door propelling member upon continuous movement of the hand wheel in one direction.
4. In a master lock operating and door propelling system for a series of cell doors where- 55 in master operating bars are arranged above

and adapted to be connected to selected doors and locks, a hand wheel; a link adjacent to the master bars connected to be moved by the hand wheel; a lever pivoted to the door propelling member and connected to said link; means connecting said lever to actuate said lock operating member upon initial movement of the hand wheel; and means to hold said lock operating member inactive while movement is imparted by the hand wheel to the door propelling member.

5. In a master lock operating and door propelling system for a series of cell doors wherein master operating bars are arranged to be connected to selected locks and doors, actuating means for said bars including a pivoted rocker member connected to the master lock operating bar; a lever pivotally connected to the master door propelling bar; operative connections between said lever and said locking member so arranged that, when said lever is initially actuated, lock operating movement is imparted to the master lock operating bar and, thereafter, door propelling movement is imparted to the master door propelling bar; and manual operating means connected to said lever arranged to be moved in one direction to unlock and open all selected doors and in the opposite direction to close and re-lock all of said doors.

6. A master lock operating and door propelling system for a series of cell doors wherein a master lock operating bar and a master door propelling bar are adapted to be selectively connected to the respective locks and doors, a common actuating means for both master bars connected and arranged first to impart lock actuating movement to the master lock operating bar, and, thereafter, to impart door propelling movement to the master door propelling bar independently of the master lock operating bar; said actuating means including a manually operable device adapted to be moved continuously in one direction to unlock, open and lock open all doors connected to said bars and to be moved in the opposite direction to close and relock said doors.

7. In a master lock operating and door propelling system for a series of cell doors wherein a master lock operating bar and a master door propelling bar are arranged to be connected to selected locks and doors, selector mechanism for effecting the connections to said locks and doors; a common actuating system for both master bars including a series of levers and links operatively connected to said bars and so related to each other that separate actuating movements are imparted to the respective bars independently of each other; and a single manual actuating member connected to said system of links and levers and arranged to impart actuating movement to both bars upon being moved continuously in either direction.

8. In a master lock operating and door propelling system for a series of cell doors wherein independent master operating members are arranged to be connected to selected locks and doors, selector mechanism for effecting such connections; a common actuating device connected to impart lock actuating movement to the master lock operating member independently of the master door operating member and then to impart door propelling movement to the master door propelling member independently of the master operating member; and means located at a single operating station connected to actuate both of said master members upon continuous and uninterrupted movement in either direction.
9. In a master lock operating and door propelling system for a series of cell doors wherein a master lock operating bar and a master door propelling bar are arranged in a housing above the series of doors, selector mechanism adapted to connect selected locks and doors to the respective bars; common actuated mechanism for the bars including a substantially T-shaped rocker member pivoted within the housing and having an actuating arm connected to the master lock operating bar; a bell crank lever pivotally connected to the master door propelling bar and adapted to move bodily therewith; operative connections between said bell crank lever and one arm of said T-shaped rocker member arranged to impart rocking movement thereto when the bell crank lever is pivotally actuated; and a single actuating hand wheel connected to impart both pivotal and bodily longitudinal movement to said bell crank whereby to transmit actuating movements to the respective master bars in the proper sequence.
10. In a master lock operating and door propelling system for a series of cell doors wherein a master lock operating bar and a master door propelling bar are arranged in a housing above the series of doors, selector mechanism adapted to connect selected locks and doors to the respective bars; common actuated mechanism for the bars including a substantially T-shaped rocker member pivoted within the housing and having an actuating arm connected to the master lock operating bar; a bell crank lever pivotally connected to the master door propelling bar and adapted to move bodily therewith; operative connections between said bell crank lever and one arm of said T-shaped rocker member arranged to impart rocking movement thereto when the bell crank lever is pivotally actuated; means for limiting the pivotal movement of said bell crank lever; and a single manually operable device connected to said bell crank lever to impart actuating movements to said master bars in the proper sequence.
11. In a master lock operating and door propelling system for a series of cell doors wherein a master lock operating bar and a master door propelling bar are arranged in a housing above the series of doors, selector mechanism adapted to connect selected locks and doors to the respective bars; common actuated mechanism for the bars including a substantially T-shaped rocker member pivoted within the housing and having an actuating arm connected to the master lock operating bar; a bell crank lever pivotally connected to the master door propelling bar and adapted to move bodily therewith; operative connections between said bell crank lever and one arm of said T-shaped rocker member arranged to impart rocking movement thereto when the bell crank lever is pivotally actuated; and a single actuating hand wheel connected to impart both pivotal and bodily longitudinal movement to said bell crank whereby to transmit actuating movements to the respective master bars in the proper sequence.
12. In a master lock operating and door propelling system for a series of cell doors wherein a master lock operating bar and a master door propelling bar are arranged in a housing above the doors; selector mechanism for selectively connecting any of the locks and doors to said bars; a fixed bracket within the housing presenting a vertical flange parallel with said master bars; a T-shaped rocker member pivoted adjacent to the junction of its arms to said fixed bracket and having one arm pivotally connected to the master lock operating bar; the other arm of said T-shaped member presenting an open channel adjacent to the vertical flange of said fixed bracket; a bell crank lever pivotally connected at the junction of its arms to the master door propelling member and arranged to move bodily therewith; said vertical flange of the fixed bracket member presenting a longitudinal slot; a pin fixed on the end of one of the arms of said bell crank lever and extending through said longitudinal slot into the channel in said T-shaped locking member and arranged to impart rocking movement thereto when said bell crank lever is pivotally actuated; and a single actuating device connected to said bell crank lever whereby to effect sequential actuation of the selected locks and doors.
13. In a master lock operating and door propelling system for a series of cell doors wherein a master lock operating bar and a master door propelling bar are arranged in a housing above the doors, selector mechanism for connecting selected ones of the locks and doors to said bars; a bracket fixed in the housing adjacent to said bars and presenting a substantially vertical flange; a rocker member pivoted to said bracket having one arm

pendently to said master bars in the proper sequence.

11. In a master lock operating and door propelling system for a series of cell doors wherein a master lock operating bar and a master door propelling bar are arranged in a housing above the series of doors, selector mechanism adapted to connect selected locks and doors to the respective bars; common actuating mechanism for the bars including a substantially T-shaped rocker member pivoted within the housing and having an actuating arm connected to the master lock operating bar; a bell crank lever pivotally connected to the master door propelling bar and adapted to move bodily therewith; operative connections between said bell crank lever and one arm of said T-shaped rocker member arranged to impart rocking movement thereto when the bell crank lever is pivotally actuated; and a single actuating hand wheel connected to impart both pivotal and bodily longitudinal movement to said bell crank whereby to transmit actuating movements to the respective master bars in the proper sequence.

12. In a master lock operating and door propelling system for a series of cell doors wherein a master lock operating bar and a master door propelling bar are arranged within a housing above the doors; selector mechanism for selectively connecting any of the locks and doors to said bars; a fixed bracket within the housing presenting a vertical flange parallel with said master bars; a T-shaped rocker member pivoted adjacent to the junction of its arms to said fixed bracket and having one arm pivotally connected to the master lock operating bar; the other arm of said T-shaped member presenting an open channel adjacent to the vertical flange of said fixed bracket; a bell crank lever pivotally connected at the junction of its arms to the master door propelling member and arranged to move bodily therewith; said vertical flange of the fixed bracket member presenting a longitudinal slot; a pin fixed on the end of one of the arms of said bell crank lever and extending through said longitudinal slot into the channel in said T-shaped locking member and arranged to impart rocking movement thereto when said bell crank lever is pivotally actuated; and a single actuating device connected to said bell crank lever whereby to effect sequential actuation of the selected locks and doors.

13. In a master lock operating and door propelling system for a series of cell doors wherein a master lock operating bar and a master door propelling bar are arranged in a housing above the doors, selector mechanism for connecting selected ones of the locks and doors to said bars; a bracket fixed in the housing adjacent to said bars and presenting a substantially vertical flange; a rocker member pivoted to said bracket having one arm

- 5 pivotally connected to said master lock operating bar and another arm presenting a channel adjacent to said vertical flange on said bracket; a bell crank lever pivotally connected at the junction of its arms to the master door propelling bar and arranged to move bodily therewith; said vertical flange having a longitudinal slot parallel with the master propelling bar; a pivot pin for the bell crank lever extending through said longitudinal slot and part-way into said channel in the rocker member; a pin on the end of one of the arms of said bell crank lever also extending through said longitudinal slot into the bottom of said channel and arranged to impart rocking movement thereto when said bell crank is pivotally actuated; said channel member presenting a slot at one side to permit swinging movement thereof with respect 10 to the pivot pin of said bell crank lever; said vertical flange having an arcuate slot communicating with one end of said longitudinal slot to permit swinging movement of said pin on the bell crank arm whereby to impart the desired rocking movement to said rocker member; and a single manual actuating device arranged at a master control station and connected to impart actuating movements to said bell crank lever.
- 15 30 14. In a master lock operating and door propelling system for a series of cell doors wherein a master lock operating bar and a master door propelling bar are arranged in a housing above the doors, selector mechanism 20 for connecting selected ones of the locks and doors to said bars; a fixed bracket in the housing adjacent to said bars and presenting a substantially vertical flange; a rocker member pivoted to said bracket having one arm 25 pivotally connected to said master lock operating bar and another arm presenting a channel adjacent to said vertical flange on said bracket; a bell crank lever connected at the junction of its arms to the master door propelling bar and arranged to move bodily therewith; said vertical flange having a longitudinal slot parallel with the master propelling bar; a pivot pin for the bell crank lever extending through said longitudinal slot and part-way into said channel in the rocker member; a pin on one of the arms of said bell crank lever also extending through 30 said longitudinal slot into the bottom of said channel and arranged to impart rocking movement thereto when said bell crank is pivotally actuated; said channel member presenting a slot at one side to permit swinging movement thereof with respect to the pivot pin of said bell crank lever; said vertical flange having an arcuate slot communicating with one end of said longitudinal slot to permit swinging movement of said pin on the bell crank arm whereby to impart the desired 35 rocking movement to said rocker member; a hand wheel arranged at a master control station; an operating link pivotally connected to the other arm of said bell crank lever and guided to move longitudinally; a rack associated with said link; a pinion meshing with said rack; and operating connections between said hand wheel and said pinion.
- 40 45 50 55 60 65 70 75 80 85 90 95 100 105 110 115 120 125 130
- 45 50 55 60 65 70 75 80 85 90 95 100 105 110 115 120 125 130
- link operatively connected to said bell crank lever; and gearing connecting the hand wheel to reciprocate said link whereby to impart separate actuating movements to the master bars upon rotation of the hand wheel.
15. In a master lock operating and door propelling system for a series of cell doors wherein a master lock operating bar and a master door propelling bar are arranged in a housing above the doors, selector mechanism for connecting selected ones of the locks and doors to said bars; a bracket fixed in the housing adjacent to said bars and presenting substantially vertical flange; a rocker member pivoted to said bracket having one arm pivotally connected to said master lock operating bar and another arm presenting a channel adjacent to said vertical flange on said bracket; a bell crank lever connected at the junction of its arms to the master door propelling bar and arranged to move bodily therewith; said vertical flange having a longitudinal slot parallel with the master propelling bar; a pivot pin for the bell crank lever extending through said longitudinal slot and part-way into said channel in the rocker member; a pin on one of the arms of said bell crank lever also extending through said longitudinal slot into the bottom of said channel and arranged to impart rocking movement thereto when said bell crank is pivotally actuated; said channel member presenting a slot at one side to permit swinging movement thereof with respect to the pivot pin of said bell crank lever; said vertical flange having an arcuate slot communicating with one end of said longitudinal slot to permit swinging movement of said pin on the bell crank arm whereby to impart the desired rocking movement to said rocker member; a hand wheel arranged at a master control station; an operating link pivotally connected to the other arm of said bell crank lever and guided to move longitudinally; a rack associated with said link; a pinion meshing with said rack; and operating connections between said hand wheel and said pinion.
16. In a master lock operating and door propelling system for a series of cell doors wherein a master lock operating bar and a master door propelling bar are arranged within a housing above the doors, means for selectively connecting any of the locks and doors to said bars; a bell crank lever pivotally connected to the master propelling bar and arranged to move bodily therewith; means to limit the pivotal movement of said bell crank lever; a pivoted arm connected to impart lock actuating movements to said master lock operating bar; operative connections between said bell crank lever and said pivoted arm whereby movement is imparted to the master lock operating bar when said bell crank lever is pivotally moved; and a

single actuating device operatively connected to said bell crank lever first to impart swinging movement to it and then to move it bodily with said master door propelling bar.

- 5 17. In a master lock operating and door propelling system for a series of cell doors wherein a master lock operating bar and a master door propelling bar are arranged within a housing above the doors, selector mechanism for selectively connecting any of the locks and doors to said bars; a fixed bracket within the housing; a rocker pivotally connected to said fixed bracket and to the master lock operating bar; an actuating lever connected to the master door propelling bar; operating connections between said actuating lever and said rocker member whereby to transmit lock actuating movements to said master lock operating bar; and a single manually operable device located at a master control station operatively connected to said actuating lever and arranged to be moved in one direction successively to impart lock actuating and door propelling movements to said master bars.

18. In a master lock operating and door propelling system for a series of cell doors wherein a master lock operating member and a master door propelling member are ar-

- 30 ranged to be selectively connected to any of the locks and doors, common means for effecting actuating movements of said members in succession whereby selected doors may be unlocked and opened or closed and re-locked by a single operation of said means; and a hand wheel connected to said actuating means.

19. In a master lock operating and door propelling system for a series of cell doors 40 wherein a master lock operating bar and a master door propelling bar are adapted to be selectively connected to any of the locks and doors, an actuating lever operatively connected to said master door propelling bar:

- 45 means permitting limited pivotal movement of said actuating lever with respect to said master door propelling bar; operative connections between said lever and said master lock operating bar whereby lock actuating movements are imparted to said master lock operating bar when said lever is pivotally moved; and a single actuating member connected to impart both pivotal and bodily longitudinal movements to said lever and so arranged as to effect the actuation of the selected locks and doors when the actuating member is moved continuously in one direction.

20. In a master lock operating and door propelling system for a series of cell doors 60 wherein a master lock operating bar and a master door propelling bar are adapted to be selectively connected to any of the locks and doors, an actuating lever operatively connected to said master door propelling bar;

means permitting limited pivotal movement of said actuating lever with respect to said master door propelling bar; operative connections between said lever and said master lock operating bar whereby lock actuating movements are imparted to said master lock operating bar when said lever is pivotally moved; means to impart locking movement to the master lock operating bar when selected doors are unlocked and opened incident to the door propelling movement of said lever; and a single actuating device connected to said lever to effect said operations.

21. In combination with a cell door, lock operating and door propelling mechanism arranged above the door including separate members connected to actuate the lock and to propel the door; means connected to both members and arranged to impart successive actuating movements thereto; and a single operating device connected to said means.

22. In combination with a cell door, a lock operating bar and door propelling bar common actuating mechanism connected to both bars and having means to impart actuating movement, first, to one bar and, then, to the other bar; and a single, manually operable device connected to deliver power to said actuating mechanism.

23. In combination with a cell door, a lock operating bar and door propelling bar common actuating mechanism connected to both bars and having means to impart actuating movement, first, to one bar and, then, to the other bar; and means connected to deliver motive power to said mechanism.

24. In a lock operating and door propelling system for cell doors having movable bars arranged to be selectively connected to the locks and doors; a single manually operable device; and power delivering connections between said manually operable device and said bars arranged to impart sequential movements to the bars.

25. In a lock operating and door propelling system for cell doors having movable bars arranged to be selectively connected to the locks and doors; a single operating hand wheel; and power delivering mechanism connecting the hand wheel to actuate said bars in sequence upon continuous movement of the hand wheel in one direction.

In testimony that we claim the foregoing as our own, we have hereto affixed our signatures.

L. J. WHITE.
